(57) **CLAIM**

The ornamental design for a line clamp, as shown and described.

DESCRIPTION

FIG. 1 is an elevated front perspective view of a line clamp in accordance with the present invention in an open state;

FIG. 2 is an elevated front perspective view of the line clamp in a closed state clamped about a power line shown in phantom;

FIG. 3 is an elevated back perspective view of the line clamp in an open state received on a power line shown in phantom; FIG. 4 is an elevated back perspective view of the line clamp in a closed state clamped about the power line;

FIG. 5 is a lower front perspective view of the line clamp in an open state;

FIG. 6 is a top view of the line clamp;

FIG. 7 is a bottom view of the line clamp;

FIG. 8 is a front view of the line clamp in an open state;

FIG. 9 is a front view of the line clamp in a closed state;

FIG. 10 is a back view of the line clamp in an open state;

FIG. 11 is a back view of the line clamp in a closed state;

FIG. 12 is a right side view of the line clamp in an open state;

FIG. 13 is a right side view of the line clamp in a closed state;

FIG. 14 is a left side view of the line clamp in an open state; and,

FIG. 15 is a left side view of the line clamp in a closed state.

The broken lines in the figures depict portions of the line clamp that form no part of the claimed design.
